Atty.*

UNITED STATES PATENT OFFICE.

MARC GRANDJEAN, OF PARIS, FRANCE.

REMOVABLE ARTICULATED STRIKER CYLINDER FOR STENOGRAPHIC AND LIKE MACHINES.

Application filed December 13, 1921. Serial No. 522,103.

To all whom it may concern:

Be it known that I, MARC GRANDJEAN, a citizen of the Republic of France, and residing at Paris, Seine Department, Bourse 5 du Commerce, Rue du Louvre, in the Republic of France, industrial, have invented certain new and useful Removable Articulated Striker Cylinders for Stenographic and like Machines, of which the following is 10 a specification.

My invention relates to a removable platen for stenographic and like machines whereof the principle characteristic consists in the fact that the said platen is adapted 15 to assume the operative position and to be instantly withdrawn therefrom by pivoting upon a shaft, thereby providing for the different operations of the machine and especially for the insertion and removal of paper 20 in sheets or strips which is used in the printing of the characters.

The accompanying drawing is a diagrammatic view of an embodiment of the invention.

25 The device consists essentially of a shaft 1 secured to a pivot 2 which is revolute in the bearings 3 mounted upon the machine frame. The other end of the shaft 1 is held in the operative position in a notch 4 in the 30 machine frame by a catch 5 pivoted thereon and submitted to the action of the spring 6. A spring 7 acting upon the pivot 2 effects the upward return of the shaft 1, in such manner that by releasing the fastening 35 catch 5, the shaft and the platen 8 mounted thereupon will be automatically raised, the action thus tending to give the movable portion the position shown in dotted lines.

To bring the platen into the operative 40 position, the movable portion is caused to pivot in the downward direction by acting

on the button 9 disposed on the end of the shaft 1; the spring 7 is now set, and the shaft 1 pushes aside the said catch and enters the notch 4; the spring 6 returns the 45 said catch upon the shaft 1 which is thereby held in place against the effort of the spring 7 tending to withdraw the same.

The platen is loosely revolute on the shaft 1 and is held in place upon the latter 50 at one end by the pivot 2 and at the other end by a stop ring 10. The platen has disposed on the end thereof a driving member 11 connected with the mechanism of the said machine which effects the rotation of the same in the proper sense and to the required extent according to circumstances. The paper may be drawn along by means of one or more rollers 12 which are pressed against the platen by suitable 55 springs, not shown, and providing for the movement of the paper by adhesion as in the case of typewriting machines.

Claim:

In a stenographic machine, the combination 60 of a rod provided at one of its ends with transverse horizontal pivots, a spring which tends to raise the said rod about the said pivots, locking means engaging the opposite end of the rod in order to maintain 65 the same in the lowered position, a cylindrical platen rotatably mounted on this rod and a driving member secured to the said platen and which serves for the mechanical driving 70 of the latter.

In testimony, that I claim the foregoing as my invention I have signed my name in presence of two subscribing witnesses.

MARC GRANDJEAN.

Witnesses:

JOHN F. SIMONS,
MAURICE ROUX.
